US00D541771S

(12) **United States Design Patent** (10) Patent No.: **US D541,771 S**
(45) Date of Patent: **** May 1, 2007**

(54) **DMB RECEIVER**

(75) Inventor: **Yeon-Moo Chung**, Seoul (KR)

(73) Assignee: **Samsung Electronics Co., Ltd.**,
Kyunggi-do (KR)

(**) Term: **14 Years**

(21) Appl. No.: **29/243,981**

(22) Filed: **Dec. 2, 2005**

(51) **LOC (8) Cl. 14-03**

(52) **U.S. Cl. D14/126**

(58) **Field of Classification Search** D14/125-134,
D14/239, 371, 136, 374-377; 312/7.2; 348/836,
